UNITED STATES PATENT OFFICE.

JOHN B. WHITE, OF SPOKANE, WASHINGTON.

DESIGN FOR A TIRE TREAD.

Application filed February 7, 1924. Serial No. 8,565. Term of patent 7 years.

To all whom it may concern:

Be it known that I, JOHN B. WHITE, residing at Spokane, in the county of Spokane and State of Washington, have invented a new, original, and ornamental Design for Tire Treads, of which the following is a specification, reference being had to the accompanying drawing, forming part thereof.

In the drawings,—

Figures 2 and 3 are sectional views, respectively, on the planes indicated by the lines 2—2 and 3—3, of Figure 1.

I claim:

The ornamental design for a tire tread, as shown.

JOHN B. WHITE.
